UNITED STATES PATENT OFFICE.

PONTUS OSTENBERG, OF SANTA CLARA COUNTY, CALIFORNIA, ASSIGNOR TO MANUEL ADRIAN, OF SAN JOSE, CALIFORNIA.

INTERNAL-COMBUSTION ENGINE.

1,341,152.

Specification of Letters Patent. Patented May 25, 1920.

Application filed February 25, 1919. Serial No. 279,203.

To all whom it may concern:

Be it known that I, PONTUS OSTENBERG, a citizen of the United States, and resident of Santa Clara county, in the State of California, have invented certain new and useful Improvements in Internal-Combustion Engines, of which the following is a specification.

My invention relates broadly to the arrangement of the magneto, governor, carbureter and water pump of an engine with relation to the engine base and cylinder, and particularly to the combination of the water pump with the other devices mentioned.

It is the object of my invention to provide such an arrangement of the magneto, governor, carbureter and water pump, together with such working parts as may be connected thereto, as to secure synchronous action between the same at all times and at the same time simplify the construction and operation of the several members.

With these and other objects in view my invention consists of the novel and useful provision, formation, construction, combination and relative arrangement of parts, members and features all as hereinafter described, shown in the drawings and finally pointed out in the claims.

In the drawings:—

Fig. 1 is a side elevation of an engine and its base embodying my invention.

Fig. 2 is a vertical sectional view through the governor in position on the vertical shaft forming a part of my invention.

Fig. 3 is a sectional view on line 3—3 of Fig. 2.

Fig. 4 is a diagrammatical plan view of the throttle valve and its connections to the governor.

Fig. 5 is a sectional view on line 5—5 of Fig. 1.

Similar characters of reference indicate similar parts throughout the several views.

Referring now more particularly to the drawings, 1 is the engine base and 2 the cylinder mounted thereon, the crank shaft being shown at 3 and having a gear 4 mounted thereon. At 5 is shown a shaft operating in bearings 6 and parallelly disposed with relation to the said cylinder 2. Shaft 5 is operated through the medium of gear 7 mounted thereon and meshing with gear 4. To the upper end of shaft 5 is connected a

magneto 8 the same being mounted securely on cylinder 2 and connected to a spark plug as 9 by wire 10. Between the shaft 5 and the magneto shaft 11 is inserted an impulse starter as 12, of any suitable form such as disclosed in my Patent No. 1,291,097, of January 14, 1919.

At 13 is shown a governor bowl fixedly mounted on shaft 5 and opening upwardly and having a recess 14 formed in the bottom thereof in which are mounted weighted 65 rocker-arms 15 on pivots 16, said recess 14 being adapted to hold a quantity of lubricating oil 17. Rocker-arms 15 support a member 18 freely movable in a vertical direction but prevented from moving sidewise 70 off of arms 15 by the side walls of recess 14. Supported in turn on member 18 is a freely movable member 19 which projects sufficiently far up the shaft 5 to engage one end of the throttle operating lever 20. 75 Lever 20 is pivoted at any suitable point as 21 and is attached by its shorter arm to the stem 22 of valve 23, a complete disclosure of the preferred form of the throttle being made in the application signed by me on the 19th day of February, 1919, Serial Number 279,207, filed Feb. 25, 1919, and entitled Carbureter. The action of the rocker-arms 15, when shaft 5 is rapidly revolved is to lift members 18 and 19 and thereby operate 85 throttle 23 through the medium of lever 20.

To the lower end of shaft 5 and preferably below gear 7, is placed a gear water pump 24. The first gear 25 is mounted on shaft 5 and the second gear 26 meshing 90 therewith is an idler mounted in casing 27 and both gears revolving in the direction indicated by the arrows. Water is admitted at 28 through pipe 29 from a source of supply not shown and is carried by the meshing gears to pipe 30 through which it is forced to the water jacket of cylinder 1. An overflow is of course supplied at some suitable point as at 31.

In the construction and arrangement as 100 above set forth it is clear that different forms of magnetos and governors may be used with or without an impulse starter or with or without a water pump, but I have found that the greatest economy and 105 efficiency both in manufacturing and in operation is secured by combining on the one driving shaft a magneto, an automatic im-

pulse starter, a governor adapted to carry its own lubricating oil, and a simple gear water pump.

It is understood, of course, that changes 5 in form, construction, arrangement and operation may be made within the scope of the appended claims.

I claim:

1. The combination with a water cooled 10 engine of the type disclosed, of a single crank-shaft driven shaft vertically and revolvably mounted on the exterior thereof, a water pump, a governor, an impulse starter, and a magneto operatively mounted in axial 15 alignment with said shaft and operated by the revolution thereof, and a throttle operating lever arranged to be actuated by the operation of said governor.

2. The combination with a water cooled 20 engine of the type disclosed, of a single crank-shaft driven shaft vertically and revolvably mounted on the exterior thereof, a water pump, a governor, an impulse starter, and a magneto operatively mounted 25 in axial alignment with said shaft and operated by the revolution thereof, the said governor comprising a bowl secured to said shaft and having a chamber adapted to con-

tain lubricating oil, weighted arms pivotally mounted in said chamber, a sleeve concentrically mounted on said shaft and actuated by said governor, and a throttle operating lever arranged to be actuated by the operation of said sleeve.

3. The combination with an engine of 35 the type disclosed, of a single driven shaft revolvably mounted on the exterior thereof in parallel relation to the cylinder thereof, a gear mounted on the crank shaft of the engine, a gear meshing therewith, mounted 40 on said driven shaft, a water pump operatively connected to one end of said driven shaft adjacent said crank shaft, a governor concentrically mounted upon said drive shaft adjacent said crank shaft, throttle 45 lever engaging means operated by said governor concentrically mounted on said drive shaft above said governor, an impulse starter concentrically mounted upon said drive shaft a distance above said throttle lever engaging means, and a magneto mounted in axial alignment with said drive shaft and in operative engagement with said impulse starter.

Executed this 19th day of February, 1919. 55
PONTUS OSTENBERG.
